UNITED STATES PATENT OFFICE.

ULYSSES GRANT HOUSTON, OF MANHATTAN, KANSAS.

DESIGN FOR AN EDUCATIONAL MODEL.

SPECIFICATION forming part of Design No. 18,409, dated June 26, 1888.

Application filed April 28, 1888. Serial No. 272,214. Term of patent 14 years.

To all whom it may concern:

Be it known that I, ULYSSES GRANT HOUSTON, a citizen of the United States, residing at Manhattan, in the county of Riley and State 5 of Kansas, have invented and produced a new and original Design for an Educational Model, reference being had to the accompanying photographic illustration, forming part thereof.

The figure is an elevation of my design.

10 This design may represent the larger portion of the solar system and various views in different countries and representations of art.

S illustrates the sun; E, the earth, and M its moon; M', Mercury; V, Venus. N is Mars, and 15 J is Jupiter and L some of its satellites.

K is Saturn and its satellites, also rings.

O is Uranus and satellites.

B is Neptune and satellites.

P P are fixed stars, and C a comet.

20 Z V' V' represent a Mexican scene, consisting of tents and native people thereby, and W X Y represent the ruins of an Aztec temple in the rear or background.

At R is a view of the English University, I, 25 near Athens, Greece, and 4 represents a body of people adjacent thereto. On the left of these is a vessel, 3, and a locomotive-engine, 2.

At 7 is a view of a church, 6, near Rome, Italy; and Q are twelve configurations representing the twelve Apostles. 30

8 is a view of a cross.

10 and 11 are platforms, and 9 is a statue of a person on platform 10.

13 14 14 represent a mosque near Jerusalem, and 18 represents the book Koran. 35

15 represents the bottom of the mosque, and 16 is a tomb.

I claim—

A design for an educational model, consisting of the configuration of the solar system as 40 represented at A, the Mexican scene of tents and people at Z V' V', and the ruins of an Aztec temple at W X Y, the Grecian scene, consisting of the building I and people 4 at the left, the sail-vessel 3 and locomotive-engine 2, the 45 scene in Italy, consisting of the church 6, configurations of the Apostles, Q, cross 8, platforms 10 and 11, and image 9, the mosque 13 14 14 15, Koran 18, and tomb 16, as shown.

ULYSSES GRANT HOUSTON.
